UNITED STATES PATENT OFFICE.

RALPH GROSS, OF BUFFALO, NEW YORK.

AUTOMATIC RAILWAY SIGNAL.

Application filed January 14, 1926. Serial No. 81,138.

This invention relates to railroad signaling apparatus and has as one of its objects to provide an electrically controlled device actuated by means carried on the locomotive 5 to move a semaphore arm at the roadside in advance of an approaching train.

Another object is to provide a colored signal light within the cab of a locomotive, these lights being controlled by the same current 10 and which indicate the entrance and exit of the train from the signal zone, these signals being visible to an engineer irrespective of darkness.

A further object is to provide a mechanically operated register, also under the control of the same current, and having a recording means actuated thereby.

Another object is to provide such apparatus in the form of a small compact attachment readily applied to a locomotive cab without any material change therein and without interference with the usual paraphernalia contained therein.

These several objects are attained by the 25 novel construction and combination of parts hereinafter described and shown in the annexed drawing, in which:—

Figure 1 is a side elevational view of a conventional locomotive as operating on a 30 track, and illustrating the application of the invention.

Figure 2 is an enlarged sectional view of the control box, mechanism therein and semaphore mast with arm, the section being 35 taken on line 2—2 of Figure 1.

Figure 3 is a similar sectional view taken in a plane at right angles to Figure 2 on line 3—3 thereof.

In the drawing, the numeral 10 designates 40 the road bed or trackway supplied with rails on which there is a locomotive 11, shown as advancing towards a signal mast 12 having an arm 13 of the usual type pivoted near its top.

The arm is movable by an arm 14, entering 45 a switch box 15 secured to the mast, and connected to a slotted lever 16 pivoted at 17, this pivot being the terminal for a conductor 18 leading from any convenient source of electrical supply.

The lever 16 may be actuated by any of the 50 usual trackside signal control devices, not shown, and is adapted to engage either of two contacts 19 and 20 within the box 15.

Alongside the trackway are masts 21 having re-entrantly bent spring loops 22 at their

upper ends, the downturned portion of these loops being uniformly directed towards the rails and provided with spaced insulators for carrying rods 23 and 24, connected by 60 conductors 25 and 26 with the contacts 19 and 20.

A hollow casing 27 having a transparent front 28 is secured in the cab of the locomotive closely adjacent its wall 11' and mounted 65 on the outer side of the wall 11' are a pair of bowed spring contractors 29 and 30 adapted to make wiping contact respectively with the rods 23 and 24.

A small electro-motor 31 is mounted in the 70 casing 27, the same being bolted to a transverse partition 32 in the lower part of the casing, this motor driving a reducing gear train 33, the last gear of which is fixed on a spindle 34 mounted in the casing.

Fixed on the spindle is a drum 35 to wind a blank strip of paper 36 acting as a register, the blank being wound from another drum 37 mounted on a spindle near the top 75 of the casing.

A pair of styli 38 and 39 are pivoted on a rod 40, each being counterbalanced by a weight 41, and carried by the styli are armatures 42 and 43, respectively operated by electromagnets 44 and 45 carried on the 80 partition 32.

On top of the casing are light signals 46 and 47, respectively red and green and these, together with the electromagnets 44 and 45, and motor 31, are wired to receive current from the main conductor 48, as conveyed by the rails 10, through the body 90 of the locomotive to the casing 27.

The wiring is so arranged that when the semaphore arm is in a lowered position as 95 to convey current from the conductor 18, lever 16, contact 19, conductor 25, and rod 23, to the conductor 29 and thence to the lamp 47, motor 31, electromagnet 45 and ground 48.

When the motor is energized, the paper strip 36 is slowly actuated and the stylus 39 drawn into operative contact with it, recording a line equivalent to the duration of contact of the contactor 29 and rod 23.

When this contact becomes broken, the current is cut off and the motor ceases running; at the same time the green light ceases to display a signal.

In a similar manner, when the arm 13 is 110 raised, current will flow through the lower rod 24, contactor 30, lamp 46, electro-magnet

44 and motor 31, causing the stylus 38 to record upon the strip 36, thus showing the duration of the danger signal.

From the foregoing it will be seen that 5 an efficient and practical signaling device has been disclosed, and that the same can be readily and cheaply applied, acting as an auxiliary to present forms of signals and assuring that attention will be called to the 10 same.

Furthermore, the device presents a permanent record by which the action of the signals may be checked and assurance of safety supplied.

15 Having thus described my invention, what I claim as new and desire to secure by Letters Patent, is:—

In combination with a trackway having roadside signals including a movable semaphore arm and a locomotive, of masts arranged adjacent the roadside, spring arms 20

on said masts, rods insulated from said spring arms and extending contiguous to the path of the locomotive, contactors carried by said locomotive to engage with said rods respectively, a casing on the locomotive, lamps respectively red and green carried on said casing, an electric motor in said casing, a drum driven by said motor, a rolled strip of material capable of receiving 25 marks actuated by said drum, a pair of electromagnets in the casing, a stylus controlled by each magnet to mark selectively on said strip, and means controlled by the position of said semaphore arm to energize 30 said motor and selectively actuate the stylus, said means also causing selective illumination of said lamps.

In witness whereof I have affixed my signature.

GROSS, RALPH
